UNITED STATES PATENT OFFICE.

JOHN A. LELAND, OF MONTAGUE, MASSACHUSETTS, ASSIGNOR TO MILLERS FALLS COMPANY, OF MILLERS FALLS, MASSACHUSETTS, A CORPORATION OF MASSACHUSETTS.

BOW-DRILL.

1,184,759.

Specification of Letters Patent.

Patented May 30, 1916.

Application filed December 13, 1915. Serial No. 66,419.

To all whom it may concern:

Be it known that I, JOHN A. LELAND, a citizen of the United States, residing at Montague, in the county of Franklin and State of Massachusetts, have invented new and useful Improvements in Bow-Drills, of which the following is a specification.

This invention relates to so-called bow drills adapted for the use of jewelers in drilling holes in relatively soft metal, such as copper, brass, silver, etc., the drilling bit being driven by a hand-operated reciprocating motor. Said motor in the elementary type of bow drill is a bow grasped by the operator's hand and a string attached to the ends of the bow and wrapped around the bit spindle.

The invention has for its object to provide a drill the bit of which is both dirigible and rotatable by one hand of the workman, while the other hand is free to hold and control the work, the drill including a hand-operated reciprocating motor which rotates the drilling bit in one direction only, a forward rotation being given to the bit when the motor is moving in one direction, and the rotation being continued when the motor is moving in the opposite direction, so that the rotation of the bit is practically continuous.

The invention is embodied in the improvements which I will now proceed to describe and claim.

Of the accompanying drawings forming a part of this specification: Figures 1 and 2 represent elevations of different sides of a drill embodying the invention; Fig. 3 represents a section on line 3—3 of Fig. 1; Fig. 4 represents a section on line 4—4 of Fig. 3; Fig. 5 represents a side view of the driving member of the clutch hereinafter referred to; Fig. 6 represents an edge view of said driving member; Fig. 7 represents a section on line 7—7 of Fig. 1.

45 The same reference characters indicate the same or similar parts in all the views.

In the drawings forming a part of this specification: 12 represents a portable frame which includes inner and outer cross bars 50 12^a and 12^b having bearings in which a spindle 13 is journaled. One end of the spindle is provided with a chuck 14 adapted to hold various sizes of drill bits or other tools.

55 The frame carries a one-way clutch which

includes a driving member adapted to be rotated forward and backward by a hand-operated reciprocating motor as herein-after described, and a driven member connected by speed-multiplying connections 60 with the spindle and locked to the driving member only when the latter is rotating forward, the driven member and the spindle being free to rotate forward while the driving member is rotating backward so that a 65 continuous and practically uniform forward rotation may be imparted to the spindle by intermittent forward rotations of the driving member. The preferred construction of said clutch and the preferred connections between the driven member and the spindle are as follows: 15 represents the driving member, which is circular or discoidal and is adapted to be rotated in opposite directions by the said reciprocating motor, on a 70 stud 16 attached to the frame 12. The periphery of the member 15 is cut away to form one or more, and preferably three, flat faces 17 located between roller-retaining flanges 18 (Fig. 6). 80

19 represents the driven member which is formed as a sleeve having a cylindrical internal surface surrounding the periphery of the driving member 15, and a hub 20 (Fig. 3) adapted to rotate on the stud 16. The 85 internal surface of the driven member 19 cooperates with the flat faces 17 on the driving member, in forming the sides of tapering chambers formed to contain clutch rollers 21. Said rollers are confined against 90 endwise displacement by the flanges 18, as shown by Fig. 6, and bear loosely against stop pins or abutments 22 attached to the driving member 15. The arrangement is such that when the driving member is rotated forward, as indicated by the arrow x (Fig. 4), the rollers 21 are caused to move away from the abutments 22 and bind in the tapering chambers formed as above described, and thus lock the two members together so that the driven member is also rotated forward. When the driving member is rotated backward, as indicated by the arrow y (Fig. 4), the rollers are moved toward the abutments 22 and release the 105 driven member, which is therefore free to continue its forward rotation while the driving member is rotating backward, so that a practically continuous forward rotation is imparted to the driven member by 110

intermittent forward rotary movements of the driving member.

The speed multiplying connections between the driven member 19 and the spindle 13 comprise a relatively large bevel gear 25 formed on the member 19, and a relatively small bevel gear or pinion 26 formed on or attached to the spindle and meshing with the gear 25, as shown by Fig. 2.

10 The preferred motor for rotating the driving member 19 comprises a handle 27 adapted to be grasped by one hand of the operator and movable longitudinally on a guide rod 28 attached to the frame 12 substantially in alinement with the spindle 13, the handle being provided with a longitudinal cavity 29 receiving said rod, a spring 30 in said cavity bearing against the rod and normally raising the handle to the position shown by Figs. 1 and 2, and a bar 31 having a shank 31^a attached by screws 32 to a ferrule 33 on the inner end of the handle, said bar being provided with teeth 34, and constituting a rack, meshing with 20 a spur gear 35 attached by pins 36 to the driving member 15.

When the handle 27 and rack 31 are pressed downward by the operator from the position shown by Figs. 1 and 2, the rack 30 and the pinion 35 rotate the driving member forward, and when the pressure is released the spring 30 raises the handle and rack so that the driving member is rotated backward.

35 The rack is held in engagement with the pinion 35 by a pin 39 attached to the frame and bearing on the back of the rack. Said pin constitutes a guide for the rack and a stop to limit the upward movement by the 40 spring 30 and prevent separation of the frame and guide rod from the handle, the rack being provided with a stop member 40 arranged to abut against the pin 39, as indicated by Fig. 1.

45 The arrangement of the guide rod 28 substantially in longitudinal alinement with the spindle 13 renders the handle 27 and a bit carried by the spindle substantially coaxial, so that the bit is accurately guided 50 and controlled by the handle. The provision of means, such as the pin 39 and stop 40, for preventing separation of the frame and guide rod from the handle, renders the bit not only rotatable, but also dirigible by 55 one hand of the operator.

It will now be seen that the operator is able to both rotate and guide the spindle and its bit by one hand and direct the bit in any desired direction against the work, which may be held or controlled by the other hand. It will also be seen that when the handle is reciprocated somewhat rapidly the forward rotation of the spindle is continuous and practically uniform, so that 60 the bit operates not only while the handle 65

is being pressed downward by the operator, but also while the handle is being raised by the spring, and the driving member is rotating backward.

To steady the forward rotation of the 70 spindle and increase its momentum, I attach to the spindle a balance wheel 42 which is sufficiently heavy to accomplish these results.

The frame 12 and spindle 13 are preferably provided with complementary bearing members constituting an antifrictional thrust bearing sustaining end thrust on the spindle due to contact of the bit with the work. As here shown, said members include the cross-bar 12^a, a collar 43 attached to the spindle, and a circular series of small antifriction balls 44 interposed between said cross-bar and collar, as indicated by Fig. 1. Said thrust bearing permits the spindle to 85 rotate rapidly by eliminating friction due to end thrust.

The improved drill is analogous to the well known jeweler's bow drill in that the bit-carrying spindle is rotated by a reciprocating handle, but differs from the bow drill in many respects and particularly in that the spindle is adapted to be rotated continuously in a forward direction by the reciprocation of the handle.

90 The clutch, and the gearing connecting its driven member with the spindle, constitute a mechanism intermediate the spindle and the motor, adapted to, or having provisions for, imparting a continuous forward 95 rotation from the reciprocating motor to the spindle.

As implied in the foregoing description and in the following claims, I am not limited to the specific mechanism of the preferred embodiment of my improvements shown by the drawings, except as otherwise required in certain of the more limited claims.

Having described my invention, I claim: 110
 1. A drill comprising a portable frame, a rotary bit-carrying spindle carried by the frame, a handle substantially in alinement with the spindle and longitudinally movable relatively to the frame and spindle, means being provided for guiding the handle and for limiting the longitudinal movements thereof, and mechanism coöperating with the handle to rotate the spindle, the drill as a whole being dirigible and the bit-carrying 115 spindle rotatable by the handle.

120
 2. A drill comprising a portable frame having a guide rod, a rotary bit-carrying spindle carried by the frame, substantially in alinement with said guide rod, a reciprocating handle movable longitudinally on the guide rod, and mechanism coöperating with the handle to impart a continuous forward rotation to the spindle, means being provided for preventing separation of the frame 125 130

and guide rod from the handle, so that a bit carried by said spindle is dirigible and rotatable by one hand of the operator.

3. A drill comprising a portable frame having a guide rod, a rotary bit-carrying spindle carried by the frame, substantially in alinement with the guide rod, a reciprocatory handle movable longitudinally on the guide rod, and mechanism coöperating with the handle to impart a continuous forward rotation to the spindle, the frame and spindle being provided with complementary bearing members forming an antifrictional thrust bearing adapted to sustain end thrust 10 of the handle, exerted through the frame, on the spindle.

4. A drill comprising a portable frame having a guide rod, a rotary bit-carrying spindle carried by said frame, substantially in alinement with the guide rod, a one-way 20 clutch also carried by the frame and including a driving member rotatable forward and backward, a rotatable driven member and means locking the driven member 25 to the driving member when the latter is rotated forward, the driven member being free to rotate forward when the driving member is rotated backward, a reciprocatory handle mounted to slide on said guide 30 rod and movable manually in one direction, a spring adapted to move said handle in the opposite direction, a rack attached to and reciprocating with the handle, a spur gear attached to said driving member and meshing 35 with said rack, and connections between said driven member and the spindle, means being provided for preventing separation of the frame and guide rod from the handle, so that a bit carried by said spindle is dirigible 40 by said handle and rotatable continuously by the handle and spring acting alternately.

5. A drill comprising a portable frame having a guide rod, a rotary bit-carrying 45 spindle carried by said frame, substantially in alinement with the guide rod, and provided with a bevel pinion and a stud attached to the frame and extending substan-

tially at right angles with the spindle, a driving clutch member rotatable forward 50 and backward on said stud and provided with a spur gear, a driven clutch member rotatable on the stud and formed as a sleeve surrounding the driving member, means locking the driven member to the driving 55 member only when the latter is rotated forward, said sleeve having a bevel gear meshing with the said spindle pinion, a reciprocatory handle mounted to slide on said guide rod and manually movable in one direction, and a rack attached to the handle and meshing with said spur gear, means being provided for preventing separation of the frame and guide rod from the handle, so that the handle is adapted to direct a bit 60 carried by the spindle and to coöperate with the spring in imparting a continuous rotation to the bit.

6. A drill comprising a portable frame having a guide rod, a rotary bit-carrying 70 spindle carried by said frame, a one-way clutch also carried by the frame and including a driving member rotatable forward and backward, a rotatable driven member and means locking the driven member to the 75 driving member when the latter is rotated forward, the driven member being free to rotate forward when the driving member is rotated backward, a reciprocatory handle mounted to slide on said guide rod and movable 80 manually in one direction, a spring adapted to move said handle in the opposite direction, a rack attached to and reciprocating with the handle, a pinion attached to said driven member and meshing with said 85 rack, and connections between said driven member and the spindle, the frame being provided with a fixed stop member with which the rack is in sliding contact and the rack being provided with a complementary 90 stop member which coöperates with said fixed member in limiting the movement imparted to the rack and handle by the spring.

In testimony whereof I have affixed my signature.

JOHN A. LELAND.
